COMBINED HAND IRON AND WORK
MOISTENER

Shichigoro Kuno, Ogden, Utah

Application September 24, 1935, Serial No. 41,876

3 Claims. (Cl. 38—78)

This invention relates to attachments for flat-irons, sad-irons, electric irons, and the like, such as are employed in the hand pressing and hand ironing of wearing apparel, linens, and related items in the usual and customary manner, and more particularly to an attachment adapted for removable and replaceable association with a hand iron to provide convenient and efficient means readily operable to moisten or dampen the material to be ironed immediately in advance of the hand iron element, and has as an object to provide an improved attachment of the character set forth.

A further object of the invention is to provide an improved combination of work moistener attachment with a hand iron.

A further object of the invention is to provide an improved unitary work moistener attachment constructed and arranged for readily detachable cooperative association with a hand iron.

A further object of the invention is to provide an improved construction and arrangement of coating elements adapted to cooperate in the removable support of a moistener attachment on and relative to a hand iron.

A further object of the invention is to provide an improved construction and arrangement of elements forming a moisture spraying and distributing attachment adapted for removable association with a hand iron.

A further object of the invention is to provide an improved work moistener attachment which, in operative combination with a hand iron, may be readily and efficiently employed to dampen work in advance of said iron to any reasonable degree desired, which is simple and relatively inexpensive of manufacture, which is readily mountable on and removable from a conventional hand iron, and which is operable to speed and improve the quality of the ironing operating.

My invention consists in the construction, arrangement and combination of elements herein-after set forth, pointed out in my claims and illustrated by the accompanying drawing, in which—

Figure 1 is a side elevation of a conventional hand iron of electric type with which the improved attachment has been operatively associated in position for practical use. Figure 2 is a top plan view of the showing of Figure 1. Figure 3 is a side elevation of the improved moistener attachment detached from its operative mounting on an iron. Figure 4 is a fragmentary detail section, taken on the vertical median plane of the moistener attachment, as mounted. Figure 5 is

a fragmentary detail section, taken on the indicated line 5—5 of Figure 4.

In the construction of the improvement as shown the numeral 10 designates the usual base or work portion of a conventional hand iron, in this instance illustrated as of the ordinary electric type, from which base suitable brackets 11 rise in the customary spaced relation to position and support the usual handle 12 therebetween with its axis in spaced, parallel relation with the longitudinal median line of the plane lower surface of the base 10, as is conventional hand iron construction herein represented to typify hand irons as a class and without reference to their specific details of form and construction. When the hand iron is of the electric type, as shown, the base 10 normally houses the heating elements of the iron and is provided at its rear end with a suitable socket 13 adapted to receive and complete operative connection with the connector or plug 20 end of a conductor element, not shown. To provide a convenient stand or support for electric-type irons, a readily-cooled extension 14 may be provided in projecting relation with the rear end of the base 10, on which extension the iron assembly may be upended for positioning with its heated surface out of contact with the material to be ironed. All of the foregoing is common and well known construction which is illustrated and described solely to define the locus of the instant invention in a typical manner, and apart from its association with the elements and apparatus hereinafter set forth forms no part of the instant invention.

The improved work moistener is illustrated as 35 comprising a suitable container or reservoir 15, of any suitable size and specific shape and formed of any suitable material in any desired manner, which reservoir is imperforate save for a suitable filler cap indicated at 16, wherethrough the contents of the reservoir 15 may be replenished, and an upstanding, externally-threaded neck or nipple 17 opening through the top of said reservoir on the longitudinal median line thereof. The threaded neck 17 is adapted to be sealed through 40 its supporting cooperation with the threaded cap 18 of an atomizing or spray assembly, which latter comprises a spray head or junction boss 19 carried in fixed relation by the cap 18, a suction tube 20 depending from the head 19 through the neck 17 within the reservoir 15 and terminating 45 adjacent the bottom of the latter, a spray nozzle 21 extending forwardly from the head 19 and terminating in a jet opening preferably adapted for relatively wide lateral diffusion of spray, and a 55

- pressure tube 22 extending in fixed relation from the head 19 in substantial alignment with and oppositely from the nozzle 21, said tube 22 operatively communicating at its rearward end with a pressure bulb 23, of conventional resilient type. The assembly just above described corresponds closely in construction and operation with similar assemblies employed for various types of spraying and with atomizers commonly employed for the diffusion of perfumes and medications and it operates upon compression of the bulb 23 to drive a jet of air across the upper end of the suction tube 20 and outwardly of the nozzle 21, thereby producing a reduced pressure in the tube 20 and permitting the liquid contents of the reservoir 15 to rise within said tube and into the path of the air jet for discharge therewith outwardly through the jet nozzle 21 in the form of finely divided spray or mist.
- 20 To removably mount the moistener attachment in operative relation with a hand iron, an angle bracket 24 is preferably provided on and in fixed forwardly projecting relation with the forward end of the handle 12, said bracket being provided as an integral part of the original iron assembly, if desired, or being furnished as a supplementary element for attachment to said iron, as shown. The horizontal, forwardly extending leg of the bracket 24 is provided with a suitable central aperture adapted to receive the free end of a hook element 25 carried in fixed relation with the rear wall of the reservoir 15 centrally and adjacent the upper margin of said rear wall, thus removably suspending said reservoir and the spray assembly carried thereby from said bracket 24 forwardly of the handle 12. Centrally of the rear wall of the reservoir 15 and in spaced relation below the hook 25, a spring clip yoke 26 is fixed to said reservoir and opens rearwardly therefrom 40 to embracingly engage about the forward of the handle brackets 11 to removably clamp said reservoir in a relatively fixed relation with the iron assembly, the weight of the reservoir, its attachments and contents, being supported by engagement of the hook 25 with the bracket 24 while the spring yoke 26 serves to steady and retain the attachment assembly against displacement relative to the iron assembly. The cap 18 is so threaded on the neck 17 as to position the 45 jet nozzle 21 in forwardly extending relation longitudinally of the iron assembly, thereby positioning the tube 22 in corresponding longitudinal alignment with the iron assembly rearwardly from the head 19, said tube having a length such as to position the resilient bulb 23 immediately 50 above the forward portion of the handle 12, said handle preferably being formed with a suitable recess or depression 27 positioned to receive and be engaged by the under surface of said bulb 23.
- 55 To further steady the attachment assembly relative to the iron assembly, a double spring clip or clamp yoke 28 may be provided in simultaneously embracing relation with the forward end of the handle 12 and with the rearward end of the tube 22 adjacent the bulb 23, said clip serving to limit relative motion or displacement of the bulb 23 and handle 12. The jet end of the nozzle 21 is preferably directed somewhat downwardly so that the spray discharged therethrough 60 may be directed to intersect the working plane of the iron base 10 across and just forwardly of the normal travel of such iron during the ironing operation.

With the elements of the assembly arranged as shown and hereabove described, the iron is ma-

nipulated and employed in the usual conventional manner upon material to be pressed or ironed, such material having been previously dampened, if desired, or spread dry for the ironing operation, as is to be preferred with certain materials and in certain operations. The presence of the moistener attachment in no way interferes with the usual manipulation of the iron and may, of course, be removed entirely from the iron for convenience in certain operations. However, with the attachment in place, any need for additional moisture in or on the material being worked can be met by shifting the hand of the iron operator to apply pressure to the bulb 23 for consequent spray discharge through the nozzle 21 to that portion of the material immediately in advance of the iron, the said bulb 23 being so positioned on the handle 12 as to permit ready compression thereof by the thumb or adjacent hand portion of the operator. Repeated pressure 10 may be applied to the bulb 23 to thoroughly wet the material, if such be desired, or the spray discharge from the nozzle may be regulated through the bulb manipulation to give that degree of moisture most desirable in a given instance. 15

While the moistener attachment is illustrated and described in connection with an electric-type iron, it should be obvious that such attachment is adaptable to cooperative association with hand irons of any and all conventional constructions, and that said attachment could readily be formed in and as an integral part of the iron assembly at the time of manufacture thereof, if such should prove expedient or desirable. 20

Since many changes, variations and modifications in the specific form, construction and arrangement of the elements shown and described may be had without departing from the spirit of my invention, I wish to be understood as being limited solely by the scope of the appended 30 claims, rather than by any details of the illustrative showing and foregoing description. 35

I claim as my invention—

1. In operative combination, a hand flat-iron formed with a handle, an apertured bracket projecting forwardly from the forward end of said handle, a liquid reservoir formed with a hook adapted to engage said apertured bracket for suspension of said reservoir on and forwardly of said iron handle, spring-yoke means carried by said reservoir for engagement with a handle support to position and steady said reservoir relative to said iron, spray-generating means carried by and in operative association with said reservoir, said latter means including a jet nozzle 45 projecting forwardly from said reservoir and a pressure tube extending rearwardly from said reservoir across said handle bracket, spring-clip means interconnecting the rear end of said pressure tube and the forward end of said handle, 50 and a pressure bulb communicating with the rear end of said pressure tube and thereby positioned in superposed relation with and for compression against said handle.

2. A moistener attachment for hand-flat-irons, 55 comprising an apertured bracket adapted for attachment to the forward end of a flat-iron handle, a liquid reservoir formed with a hook adapted to engage said apertured bracket for suspension of said reservoir from and forwardly of said handle, 60 means on said reservoir engageable with a portion of said iron to position and steady said reservoir, spray-generating means carried by said reservoir and including a forwardly-projecting jet nozzle 70 and a rearwardly-extending pressure tube, a 75

pressure bulb carried by the rear end of said pressure tube in superposed relation with and for compression against said handle, and spring-clip means operatively interconnecting said pressure tube and handle.

5. A moistener attachment for hand-flat-irons, comprising a liquid reservoir operatively supporting a forwardly-projecting jet nozzle and a rearwardly-extending pressure tube, a pressure bulb on the free end of said pressure tube, means

including an apertured bracket fixed to the forward end of the iron handle and a hook on said reservoir engageable with said bracket for supporting said reservoir from and forwardly of said iron with said bulb positioned above and for compression against said handle, means removably interconnecting said pressure tube and handle, and means operable to position and steady said reservoir relative to said iron.

SHICHIGORO KUNO. 10
